US00D577712S

(12) **United States Design Patent**
Itoh et al.

(10) **Patent No.:** US D577,712 S
(45) **Date of Patent:** ** Sep. 30, 2008

(54) **SPEAKER**

(75) Inventors: **Satoshi Itoh**, Kadoma (JP); **Koji Sano**, Kadoma (JP); **Kazuya Yamasaki**, Kadoma (JP); **Kazuki Honda**, Kadoma (JP)

(73) Assignee: **Matsushita Electric Industrial Co., Ltd.**, Osaka (JP)

(**) Term: **14 Years**

(21) Appl. No.: **29/297,691**

(22) Filed: **Nov. 15, 2007**

(30) **Foreign Application Priority Data**

Jul. 25, 2007 (JP) 2007-020154

(51) **LOC (8) Cl.** 14-01

(52) **U.S. Cl.** D14/214

(58) **Field of Classification Search** D14/204, D14/209–216, 221; 181/143–144, 147–148, 181/150, 157, 198–199, 151, 153; 381/300–302, 381/306, 333, 345, 361–364, 386–388, 332, 381/336

See application file for complete search history.
